UNITED STATES PATENT OFFICE.

MAUDE SINCLAIR GEORGE, OF ST. LOUIS, MISSOURI.

BABY PANTS.

Application filed December 21, 1925. Serial No. 76,722.

The present invention is a garment of the type commonly known in the trade as baby pants.

The object of the present invention is to provide baby pants of the so-called all-rubber type, but so constructed as to eliminate the unpleasant appearance of the all-rubber baby pants, but retaining all of its advantages, and having the appearance of full-cut drawers of cloth material.

It is also the object of the invention to construct baby pants, as above mentioned, of an impervious inner material, and an independent pervious cloth cover, whereby the impervious material is provided with ventilating openings which are covered by the pervious cover, the inner material and the outer material being maintained in position relative to each other.

With these and other objects and features in view the invention further resides in sundry details of construction, combination and arrangement of elements which will hereinafter appear from the following detailed description and from the appended claims.

In the drawings which illustrate the preferred embodiments of the invention, as at present devised:

Fig. 1 is a face view of one embodiment of the garment with portions broken away to illustrate its construction;

Fig. 2 is a fragmentary sectional view taken substantially on line 2—2 of Fig. 1;

Fig. 3 is a sectional view taken substantially on line 3—3 of Fig. 2;

Fig. 4 is a face view of another embodiment of the invention with parts broken away to illustrate its detail construction;

Fig. 5 is a vertical sectional view taken substantially on line 5—5 of Fig. 4;

Fig. 6 is a fragmentary detail view taken substantially on line 6—6 of Fig. 4, and looking in the direction of the arrows.

Referring in detail to Figs. 1 to 3, inclusive, the baby pants comprise an outer cloth cover 10 and an inner impervious lining 11 of sheet rubber or other suitable material, the cover 10 and the lining 11 are each cut to lie coextensively to each other, and each comprise a front portion *a* and *a'*, and a back portion *b* and *b'*, respectively. These front and back portions may be integral pieces of material, or may be made of separate sections suitably joined together at their crotch portion, so as to form the seat of the garment, the upper edge of

the front portion of the lining *a'*, however, terminates at a point below the upper edge of the front portion of the cover *a*, while the upper edge of the back portion *b'* of the 60 lining is coextensive, or substantially so, with the upper edge of the back portion *b* of the cover, it being understood that the upper edges of the front and back portions of the cover are coextensive and form the 65 waist opening 17 of the garment. The side edges of the portions *a*, *a'*, *b* and *b'* are inturned, and brought in close abutting relation, as illustrated at 20, Fig. 2, and suitably secured together, such as by stitching, suitable portions of the lining and cover between the sides and the crotch portion being left unstitched to form suitable leg openings 12. The leg openings are normally contracted by an elastic band 18 disposed 70 on the outer face of the cover at the marginal edge portions of the openings 12, and are maintained in position in a hem or casing provided by a double row of stitching 14 on opposite sides of the elastic connected by 75 cross cords 15, which overlie the elastic 13. The stitching 14 penetrates the cover 10 and the lining 11 and maintains the two permanently in position. The upper edge of the lining *a'*, which terminates below the upper 80 edge of the cover, is secured to the cover at a point below its upper edge by suitable means, such as the stitching 16. The waist opening 17 is normally contracted by an elastic 18 held in position in the same manner as is the elastic 13 of the leg openings, and the stitching 15^a thereof penetrates the cover as well as the lining *b'*, whereby the lining at the waist band is maintained in 85 position.

From the above it will be seen that baby pants constructed in accordance with the above have the appearance of full-cut cloth drawers, having a ventilated front side section produced by terminating the upper edge of the lining below the waist band, which ventilating opening is covered by the cloth cover.

The cloth cover may be of light net-like material, dimity, lawn, voile, or the like.

In Figs. 4 to 6, inclusive, another embodiment of the invention is shown which is in all respects the same as the form of baby pants shown in Figs. 1 to 3, inclusive, except that the lining 11^a is not secured to the cover 10^a at the leg openings or along the side edges 20 as shown in Fig. 2. The

side edges of both the lining and the cover are secured together independently one of the other. In this embodiment the leg openings 12^a of the lining are contracted by 5 the elastic 15^b which is held in position on the lining, the same as the elastic 15 and the embodiment shown in Fig. 1, the leg openings of the cover 10^a, however, are preferably uncontracted and finished off in 10 any desired manner and protrude beyond the leg openings of the lining so that the same will be normally obscured. The leg openings of the cover 10^a may be contracted independently of the leg openings of 15 the lining, if desired.

In this form of the invention it will be observed that the impervious lining 11^a may be withdrawn and separated from the cover 10^a, as the lining is only secured to the cover 20 at the points 15^x and 16^a where the back of the lining is secured to the upper edge of the cover, and the upper edge of the front portion of the lining is secured to the front portion of the cover below the upper edge 25 of the cover, the same as in Fig. 4.

From the foregoing, it will be observed that baby pants of novel construction have been produced, composed of a lining of impervious material in the form of full pants, 30 and having attached thereto a cover of textile material having the full appearance of under-drawers, with the cover and the lining so constructed as to support each other, with the impervious lining cut away at 35 portions to form ventilated openings (particularly in the front of the garment where the moisture will not seep out when the wearer is in a reclining position), which openings are covered by the cloth material 40 in such a manner as to complete the garment, and without giving visible effects of the ventilating openings, or the impervious lining thereunder.

What I claim is:—

45 1. A unitary baby pants comprising a trunk-like garment of cloth material having waist and leg encircling openings, an independent water-proof lining within said cover and in the form of a trunk-like garment having waist and leg encircling openings, said lining having its back portion coextensive with the back portion of the cover and secured thereto, and its front portion terminating below the waist opening of said 50 cover and secured to said cover.

60 2. A unitary baby pants comprising a trunk-like cover having waist and leg openings therein and an independent trunk-like impervious lining having waist and leg openings therein, said lining being provided with a cut out portion in its upper forward parts, said lining being permanently secured to said cover at the waist and the edges of said cut out portion to maintain 65 the parts in position, the cover extending

over said cut out portions in the lining to conceal the same and to complete the garment.

3. A unitary baby pants comprising a trunk-like garment of impervious material 70 having leg openings, said leg openings being surrounded by the impervious material, the front face portion of said impervious material having its upper edge terminating below the upper edge of the rear face portion thereof, and a pervious trunk-like cover for said baby pants having the upper edge of its front and back face portion coextensive with the upper edge of the back face portion of the impervious material, 80 whereby the garment is completed and the waist opening provided, the upper edge of the front face portion of the impervious material being secured to the front face portion of the cover below the upper edge 85 of the latter, and means for contracting the leg openings of the impervious material.

4. A unitary baby pants comprising a trunk-like garment of impervious material 90 having leg openings, said leg openings being surrounded by the impervious material, the front face portion of said impervious material having its upper edge terminating below the upper edge of the rear face portion thereof, a pervious trunk-like cover for 95 said baby pants having the upper edge of its front and back face portion coextensive with the upper edge of the back face portion of the impervious material, whereby the garment is completed and the waist opening 100 provided, and the upper edge of the front face portion of the impervious material being secured to the front face portion of the cover below the upper edge of the latter, the side edges of the front and back 105 faces of the impervious material being secured together on opposite sides of the garment, respectively.

5. A unitary baby pants comprising a trunk-like outer cover of textile material 110 and an independent inner trunk-like water-proof lining within the cover, said cover and lining provided with a front and rear face portion and an intermediate crotch portion, the leg opening portions in the lining being 115 surrounded by the water-proof material thereof and secured to the leg opening portions of said cover, the end edges of the front and back portions of said cover opposing to provide the waist band of the 120 garment, means suspending the back face portion of said lining from said waist band of the cover and the front face portion of the lining from said cover below the waist band thereof, and means for contracting 125 said waist band and the leg openings in said lining.

In testimony whereof I have hereunto set my hand.

LAUDE SINCLAIR GEORGE.
